CLAIM

The ornamental design for a camera lens, as shown and described.

DESCRIPTION

FIG. 1 is a top, front and left side perspective view of a camera lens;

FIG. 2 is a top, rear and left side perspective view of the camera lens of FIG. 1;

FIG. 3 is a left side view of the camera lens of FIG. 1;

FIG. 4 is a right side view of the camera lens of FIG. 1;

FIG. 5 is a top plan view of the camera lens of FIG. 1;

FIG. 6 is a bottom plan view of the camera lens of FIG. 1;

FIG. 7 is a front view of the camera lens of FIG. 1; and,

FIG. 8 is a rear view of the camera lens of FIG. 1.

The broken lines depict portions of the camera lens in which the design is embodied that form no part of the claimed design.
